US0D1079279S

(12) **United States Design Patent** (10) **Patent No.:** **US D1,079,279 S**
(45) **Date of Patent:** **** Jun. 17, 2025**

(54) **ORAL CARE IMPLEMENT**

(71) Applicant: **Colgate-Palmolive Company**, New York, NY (US)

(72) Inventors: **Daniel Wainless**, New Brunswick, NJ (US); **Eduardo Jimenez**, Manalapan, NJ (US); **Yongchao Tian**, Yangzhou (CN)

(73) Assignee: **Colgate-Palmolive Company**, New York, NY (US)

(**) Term: **15 Years**

(21) Appl. No.: **29/911,067**

(22) Filed: **Aug. 29, 2023**

(51) LOC (15) Cl. **04-02**

(52) U.S. Cl.

USPC **D4/110; D4/104**

(58) **Field of Classification Search**

USPC D4/101, 104, 105, 110, 199; D24/156, D24/176

CPC A46B 3/00; A46B 3/06; A46B 5/00; A46B 5/02; A46B 7/00; A46B 9/00; A46B 9/04; A46B 9/10; A46B 9/1026; A46B 9/1066; A46B 9/1073; A46B 9/108; A46B 9/1086; A61C 17/00; A61C 17/16; A61C 17/20; A61C 17/222; G09B 19/0084

(57) **CLAIM**

The ornamental design for an oral care implement, as shown and described.

DESCRIPTION

FIG. 1 is a front perspective view of an oral care implement showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is an enlarged top view thereof; and,

FIG. 8 is an enlarged bottom view thereof.

The broken lines illustrating portions of the oral care implement form no part of the claimed design.

1 Claim, 4 Drawing Sheets
